Primary Examiner — S. Bryan Reinholdt, Jr.*Assistant Examiner* — Julia S Folkart(74) *Attorney, Agent, or Firm* — Howard & Howard Attorneys PLLC(57) **CLAIM**

The ornamental design for an emergency relief bed as shown and described.

DESCRIPTION

FIG. 1 is a front, top, right side perspective view of an emergency relief bed;

FIG. 2 is a rear, bottom, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The evenly spaced broken lines in the drawings and the unshaded areas within them depict portions of the emergency relief bed that form no part of the claimed design.
